UNITED STATES PATENT OFFICE.

ALBERT MALSIN, OF NEW YORK, N. Y., ASSIGNOR TO LANE BRYANT, INC., OF NEW YORK, N. Y., A CORPORATION OF NEW YORK.

DESIGN FOR A CORSET.

52,582.

Specification for Design.

Patented Oct. 15, 1918.

Application filed June 13, 1916. Serial No. 103,582. Term of patent 14 years.

To all whom it may concern:

Be it known that I, ALBERT MALSIN, a citizen of the United States, and resident of New York, in the county of New York and State of New York, have invented a new, original, and ornamental Design for Corsets, of which the following is a specification, reference being had therein to the accompanying drawing.

Fig. 2 is a front perspective view of the same.

Fig. 3 is a plan view showing the corset extended.

I claim:

The ornamental design for a corset, as shown.

In testimony whereof I hereunto affix my signature.

ALBERT MALSIN.
